(57) **CLAIM**

I claim the ornamental design for an instrument panel for automobile thereof, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view for an "instrument panel for automobile" showing my new design,

FIG. 2 is a front view thereof,

FIG. 3 is a rear view thereof,

FIG. 4 is a left-side view thereof,

FIG. 5 is a right-side view thereof,

FIG. 6 is a top view thereof,

FIG. 7 is a bottom view thereof,

FIG. 8 is an enlarged partial fragmentary end cross-sectional view restricted 8 sectional areas of FIG. 2 and FIG. 4 thereof; and,

FIG. 9 is a reference view showing the state with the light on a central area in the representation of FIG. 1 thereof.
